[57] CLAIM

The ornamental design for an air diffuser, as shown and described.

DESCRIPTION

FIG. 1 is a front perspective view of an air diffuser showing my new design;
FIG. 2 is a front elevational view thereof;
FIG. 3 is a top plan view thereof;
FIG. 4 is a bottom plan view thereof;
FIG. 5 is a right side elevational view thereof;
FIG. 6 is a left side elevational view thereof; and
FIG. 7 is an enlarged partial cross-sectional view thereof, taken along the lines 7—7 in FIG. 2, with the remaining portion shown in elevation and shown broken away for ease of illustration.
